Des. 221,708
Patented Aug. 31, 1971

221,708

ASH TRAY

Luz Wong Martinez, 700 Dolores NW,
Albuquerque, N. Mex. 87105

Filed May 18, 1970, Ser. No. 23,028

Term of patent 14 years

Int. Cl. D27—03

U.S. Cl. D85—2

FIG. 1

FIG. 2

FIG. 3

FIG. 1 is a top plan view of an ash tray showing my new design;

FIG. 2 is an elevational view partly in section; and
FIG. 3 is a perspective view thereof.

I claim:

The ornamental design for an ash tray, as shown.
